Specification of Letters Patent. Patented Jan. 14, 1919.

Application filed August 28, 1914. Serial No. 859,106.

To all whom it may concern:

Be it known that I, ALSTON D. TAYLOR, a citizen of the United States, and a resident of Omaha, in the county of Douglas and 5 State of Nebraska, have invented certain new and useful Improvements in Telegraph-Repeaters, of which the following is a specification.

My invention relates to the art of telegraphy, and particularly to telegraph repeaters, or instruments for automatically retransmitting telegraphic signals from one circuit to another. It is the object of my invention to provide in an instrument of 15 this class means by which the operators at all stations on the circuits connected by the repeater may exchange signals by operations identical with those that would be required if all were on the same circuit; to 20 provide means by which the repeating of the signals is effected solely by energy derived from the main or line-circuits, so that it is unnecessary to supply a local source or sources of energy at the repeating-station; 25 and to provide convenient means for separating or "cutting apart" the line-circuits connected with the repeating instrument, so that an operator at the repeating-station may exchange signals with operators on 30 either line-circuit independently of the other, and thus adjust the instrument for efficient operation relatively to each of the line-circuits without interference with the other. Further and more specific objects of 35 my invention will be set forth hereinafter.

In the accompanying drawings, Figure 1 is a schematic diagram of the preferred embodiment of my invention, Fig. 2 is a partial side view of the repeating instrument employed in the apparatus shown in Fig. 1, a portion of the view being a longitudinal vertical section, Fig. 3 is a partial plan view of the instrument with portions broken away to show the underlying parts, Fig. 4 is a transverse vertical section on the plane of the line $x-x$ of Fig. 2, Fig. 5 is a detail perspective view of the tumbler-levers, Fig. 6 is a schematic diagram of a modified and simpler embodiment of the invention, Fig. 7 is a similar diagram showing the operation of certain parts of the same mechanism, and Fig. 8 is a schematic diagram of a further modification or simple form of the invention.

55 In the construction of telegraphic repeat-

ing mechanism it is necessary to provide in each of two line-circuits a device such as a relay, which is connected with the other line-circuit so as to open and close said circuit in accordance with increase or decrease of electric current in the circuit by which the relay or repeating device is operated. Yet a simple inter-connection of two circuits by ordinary relays is inoperative, for the reason that when one circuit is opened, as by 60 an operator at a distant line-station, the relay at the repeating-station will open the other line-circuit, and the relay controlled by the latter circuit will in turn open the first circuit at the repeating-station, so that 65 the distant operator cannot again close the circuit on which he is working. My invention provides simple and direct means for preventing opening of the sending-circuit at the repeating-station, except when the 70 sending of the message is intentionally interrupted by an operator on the receiving-circuit.

For convenience in the following descriptions, the two main or line-circuits to be 80 operatively connected by the repeating instrument will be designated as the "east line" and "west line", and the conductors by which said circuits enter the repeating-station will be indicated by reference characters E and W, respectively. As nearly all 85 of the structural elements of the repeating instruments are in duplicate, the pairs of corresponding parts will be indicated by like reference numbers, and to distinguish 90 between said paired or duplicate parts the numerals referring to one of them will be provided with indices (').

In the structure represented in Figs. 6 and 95 7 there are provided the transmitter-magnets 1, 1', having armatures 2, 2', carried by levers 3, 3' which are pivoted respectively at 4, 4' and have springs 5, 5' arranged to pull the armatures away from the poles of the transmitter-magnets when the same are de- 100 energized. Stop-screws 6, 6' limit the movements of the armatures toward the transmitter-magnets. Adjacent to the upper ends of the armature-levers 3, 3' are the repeating-keys 7, 7' which are pivoted at 8, 8' and have 105 springs 9, 9' which normally hold the contact-pins at the upper ends of the keys against the contact-screws 10, 10'. The parts are arranged so that movement of the 110 armature 2 away from the transmitter-mag-

net 1 will actuate the repeating-key 7' and disengage the same from the contact-screw 10', while similar movement of the armature 2' will actuate the repeating-key 7 in like manner. The line E is connected with the winding of the transmitter-magnet 1, thence to the contact-screw 10, and from the repeating-key 7 to ground G. The line W is similarly connected through the winding of magnet 1', to contact-screw 10', repeating-key 7', and thence to ground. It should be noted that the ends of the armature-levers 3, 3' are not normally in contact with the repeating-keys, so that a slight initial movement 10 of each armature is necessary before the respective repeating-key is actuated to disengage the same from its contact-screw. The described mechanism may be regarded as comprising a pair of direct-repeating transmitters, each actuated by energy from one line-circuit and being adapted to open and close the other line-circuit in accordance with fluctuations of current in the line-circuit from which it is operated. On the 20 armature-levers 3, 3' are lugs 11, 11', and adjacent to said lugs are L-shaped tumbler-levers 12, 12' which are pivoted on axes 13, 13'. To the downwardly-extending arms of the tumbler-levers are pivotally connected the upper ends of diagonal rods 14, 14'. The central parts of said rods are pivotally connected with links 15, 15' which are hung on small eccentrics 16 that are carried on a transverse shaft 17 disposed midway between 30 the transmitter-magnets. The lower ends of the rods 14, 14' are each provided with a pair of adjusting-nuts 18, 19 and 18', 19', and, when the eccentrics 16 are in the position shown, the portions of the rods between 40 said pairs of nuts extend through slots in the lower portions of the armature-levers. By rotation of the shaft 17 the eccentrics may be turned so as to lower the rods to the positions shown by dotted lines in Fig. 6, at which the nuts are not engageable by the armature-levers, and the tumbler mechanism thus made inoperative. The operation of the mechanism will be apparent by reference to Fig. 7, in which 50 are shown the positions of the parts assumed when the west line-circuit is opened, as by an operator thereon preparatory to the sending of a message, while the east line-circuit is closed at all line-stations and is in condition 55 for receiving messages from the repeating-station. The opening of the line W causes a decrease of energization of the transmitter-magnet 1', so that the armature 2' is released and is pulled away from the magnet by the spring 5'. At the beginning 60 of said movement of the armature and the lever 3' the latter engages the nut 19 on the rod 14 and the tumbler-lever 12 is turned on its axis so that the end of the horizontal arm 65 of said lever passes up in front of the lug 11.

on the armature-lever 3. By further movement of the lever 3' the repeating-key 7 is engaged and actuated so as to open the east line-circuit at the contact 10. When the east line is opened at the contact 10, however, the lever 3 is prevented by the tumbler-lever 12 from moving far enough to open the west line at the contact 10', and the west line thus remains intact through the repeating-station, so that when the operator on 70 said line closes his key the circuit is re-established and all the parts of the apparatus return to normal position. The space between the nuts 18 and 19 may be so adjusted that when the magnet 1' is reenergized (the 75 parts being in the positions shown in Fig. 7) the lever 3' can move far enough to permit closing of the east line-circuit at the contact 10 before the nut 18 is engaged to actuate the tumbler-lever 12 to normal position. 80 By the closing of the east line-circuit the magnet 1 is energized and moves the lever 3 far enough to disengage the lug 11 from the tumbler-lever 12, so that there is no drag or friction between said lug and the end of the 85 tumbler-lever during the returning of the latter to normal position. Should the lever 3' be moving with such rapidity as to engage the nut 18 before the magnet 1 becomes energized, the momentum of said lever 3' and its armature will be sufficient to move the tumbler-lever 12 even though the lug 11 is engaging the same. Should an operator in the east line desire to interrupt the 90 message being received from the repeating-station, he would merely open the circuit at his sending-key, after which when the sending operator on the west line closed the west circuit at his station, said circuit would immediately be opened at the repeating-station, 95 and the west operator could no longer control the line.

The repeating mechanism described may be operated satisfactorily under favorable conditions, as on short lines where there is 100 little line-leakage and where there is a comparatively strong current available for the energization of the transmitter-magnets 1 and 1'; but, owing to the fact that the armature-levers which actuate the repeating-keys 7, 7' are also employed to actuate the tumbler-levers, the mechanism is not sufficiently sensitive to be desirable for use under unfavorable operating conditions. In Fig. 8 there is illustrated a more sensitive 110 mechanism, wherein the tumbler-levers are not operated directly by the armature-levers.

In the construction shown in Fig. 8, the transmitter-magnets, the armature-levers, the repeating-keys, and the contacts therefor, and the circuit connections of the east and west lines, are substantially identical with those already described in connection with the structure shown in Figs. 6 and 7, and the like parts are designated by the 120 125 130

same reference numerals. The tumbler-levers 121, 121' are controlled by movements of a horizontal tumbler-rod 141 which is supported on vertically-extending links 151 which are pivotally connected with the ends of the rod and extend downwardly to bearings 152 on a stationary base-member. The ends of the tumbler-rod extend up in front of the poles of the transmitter-magnets, and are provided with armatures 142, 142' which are thus held adjacent to the magnet-poles. At the center of the tumbler-rod is a downwardly-extending arm 143 which is engageable with stop-screws 144 to limit horizontal movements of the rod. The tumbler-levers are pivoted on fixed axes 131, 131', and the downwardly-extending arms of said levers normally engage the pins 191, 191' on the upper side of the tumbler-rod. Movement of the tumbler-rod in either direction from an intermediate position, as to the dotted position thereof shown, raises the horizontal arm of the tumbler-lever at the end toward which the rod moves, so that said arm of the lever passes up in front of the lug 111, or 111' as the case may be, thereby preventing movement of the respective armature-lever sufficient to open the repeating-key controlled thereby, while the other tumbler-lever is lowered and permits free movement of the other armature-lever. Referring to the positions of the parts shown by dotted lines, the operation of the mechanism will be apparent. When the west line is opened, and before the armature-lever 3' moves far enough to open the east line-circuit at the contact 10, the tumbler-rod is moved to the dotted position by the pull of the magnet 1 on the armature 142, said magnet 1 at this moment still being energized. Then when the east line-circuit is opened at the contact 10, the lever 3 is prevented by the tumbler-lever 121 from moving sufficiently to actuate the repeating-key 7' which controls the west line, and said line is thus kept intact through the repeating-station. As before, the sending of the message by the operator on the west line can be interrupted by an operator on the east line opening said line at his station, because after such opening of the east line the position of the tumbler-rod will be reversed immediately upon the closing of the west line for a sufficient time to energize the magnet 1'. For rendering the tumbler mechanism inoperative when desired, there is provided a bridge-bar 161 which is connected by a screw 171 with the frame on which the tumbler-levers are pivoted. The bridge-bar is normally held in the raised position shown, by means of a spring 172 disposed around the screw beneath the bar. By turning the screw the bar may be pressed down to a position at which the ends thereof will engage the heel-portions of the tumbler-levers and raise the horizontal arms of said

levers above the lugs 111, 111', so that free movements of both of the armature-levers 3 and 3' is permitted.

In the preferred embodiment of my invention, illustrated in Figs. 1 to 5, inclusive, the 70 operation and structure of the more important parts of the mechanism are substantially the same as in the simpler forms of the invention hereinbefore described; but various accessory mechanism is made use of 75 which increases the sensitiveness of the instrument and enables its use on long lines and under the most adverse operating conditions.

In the repeating instrument, shown in 80 Figs. 2, 3, 4 and 5, there is provided a base-plate 20 of insulating material, which is supported on a hollow metal base 21. Along the rearward side of the base-plate 20 are disposed a series of terminal-connectors or 85 binding-posts 22, 22', 23, 23', 24, 24', 25, 25', 26 and 26', of which the electrical connections will be described hereinafter. Adjoining the front side of the base-plate are arranged a pair of triple-pole double-trans- 90 mission switches, each comprising three pivotally-mounted switch-blades, movable simultaneously into contact with either of two sets of contact-posts. The switch-blades are indicated by the numerals 27, 28, 29, 27', 95 28' and 29'; the one set of contact-posts are designated as 33, 34, 35, 33', 34' and 35'; and the other set of contact-posts as 36, 37, 38, 36', 37' and 38'. The blades of one switch are connected to each other by a bar 39 of 100 insulating material provided with a handle 40, the other switch having a like insulating connecting-bar 39' and handle 40'.

Over the central part of the insulating base-plate 20 a metal bed-plate 41 is supported by short posts 42 which rest upon and are secured to the base plate. At the ends of the bed-plate are mounted the vertical stud-posts 43, 43', and at positions intermediate between said posts and the trans- 110 verse center-line of the bed are secured the transverse vertical frame-plates 44, 44' which support the upper frame-plate 45. On the upper frame-plate 45 the key-posts 46, 47, 46' and 47' are mounted, being secured to 115 but insulated from said frame-plate. The vertical frame-plates, 44, 44' have circular openings through them, through which the inner ends of the transmitter-magnets 1, 1' extend so as to be supported thereby. To 120 the yokes 48, 48' of the transmitter-magnets are secured studs 49, 49', which extend through openings in the stud-posts. Coil springs 50, 50' are disposed around the studs between the yokes and the posts, and the outer threaded ends of the studs have nuts 51, 51' thereon which may be turned to adjust the magnets longitudinally toward and away from their respective armatures. The transmitter-magnet armatures 2, 2' are 130

formed integrally with the armature-levers 3, 3' and the latter extend upwardly through transverse slots in the frame-plate 45 between the pairs of key-posts, the levers being pivoted on screws 52, 52' which extend in from the longitudinal edges of the plate 45, as shown clearly in Fig. 4. Connecting-cords from the armature-levers to the tension-springs 5, 5' pass 10 through openings in the lower parts of the key-posts 47, 47', and the outer ends of said springs are connected with shafts 53, 53' which are rotatably mounted on the stud-posts and may be turned by means of the 15 wheels 54, 54' to adjust the tension of the springs.

On the key-posts 47, 47' are pivoted the repeating keys 7, 7', the posts having notched lugs thereon, and the pivot-pins 8, 8' extending into the notches, as shown, so 20 that the keys may be readily lifted out and replaced. The contact-screws 10, 10' extend through insulated bushings at the upper ends of the posts, and the contact-pins at the upper ends of the keys are 25 normally held in engagement with said screws by means of compression springs 90, 90', which engage the keys slightly below the pivotal axes thereof, and of which the degree of compression may be regulated by 30 screws 91, 91', arranged as shown. Stop-screws 55, 55' limit movement of the keys away from the contact-screws 10, 10'.

On the key-posts 46, 46' are mounted the 35 shunt-keys 56, 56' of which the structure is substantially identical with that of the repeating keys; springs 57, 57' being arranged to press the upper ends of the keys toward contact-screws 58, 58' which extend 40 through insulated bushings at the upper ends of the key-post; and stop-screws 59, 59' being arranged to limit movement of the 45 keys away from the contact-screws.

The upper ends of the armature-levers 3, 3' extend between the lower ends of the 50 respective pairs of shunt-keys and repeating-keys, and are provided with pins of insulating material for engagement with the keys so that electrical connection between the keys and armature-levers is prevented. The parts are so arranged and adjusted that 55 normally, or when the transmitter-magnets are energized so as to pull the armatures thereof toward the same, the upper ends of the armature-levers engage the shunt-keys, pressing them against their respective stop-screws and disengaging them from the contact screws at the upper ends of the key-posts. When the transmitter-magnets are 60 deenergized and the armature-levers are free to move, the springs 5, 5' pull the upper ends of the armature-levers toward the repeating-keys, pressing them against the stop-screws 55, 55' and disengaging them 65 from the contact-screws 10, 10'. It should

be noted that the transmitter-magnet 1 controls the keys 7' and 56', while the transmitter-magnet 1' controls the keys 7 and 56,

On the central part of the bed-plate 41, midway between the transmitter-magnets, 70 are mounted the pivot-posts 60. In the upper ends of said posts are screws 61 between which is pivotally mounted the tumbler-shaft 62. On the central part of 75 said shaft is secured an arm 63 which extends upwardly through a transverse slot in the upper frame-plate 45, and carries at its upper end a double-armature 64. Tumbler-magnets 65, 65' are arranged so that the poles thereof are in proximity to said 80 armature, the said magnets resting on the base-positions of the key-posts 46, 47, 46' and 47'. The yokes of the tumbler-magnets have 85 studs 66, 66' secured thereto, which extend horizontally through openings in the upper 90 ends of the stud-posts 43, 43', and on their outer threaded ends are provided with the adjusting-nuts 67, 67'. Springs 68, 68' engage shoulders on the studs, so that by turning the nuts 67, 67' the magnets may be 95 adjusted longitudinally toward and away from the armature, similarly to the transmitter-magnets. Movement of the arm 63 is limited by stop-screws 69, 69' which extend through the plate 45 from the ends thereof, as shown. 99 Pivoted on the tumbler-shaft 62 are tumbler-levers 122, 122', having arms which extend diagonally toward the armatures 2, 2' and terminate adjacent to lugs 112, 112' on 100 said armatures. The tumbler-levers also have short arms which extend vertically adjacent to the arm 63 and carry screws 70, 70' of which the ends normally engage said arm 63, being held against the same by means of a flat spring 71 which is secured on the 105 lower end of the arm 63, and of which the end-portions engage and press upwardly the diagonal arms of the tumbler-levers.

Above the diagonal arms of the tumbler-levers are cams 72, 72' carried on shafts 73, 73' which are revolvably mounted in lugs which extend down from the plate 45. By turning the shafts the cams may be moved to positions at which they will engage and depress the diagonal arms of the tumbler-levers, bending the spring 71, and moving the stop-screws 70, 70' out of engagement with the arm 63. When the tumbler-levers are depressed by the cams, as described, the ends of the diagonal arms are held at positions such that neither of said arms can be engaged by the lugs 112, 112' during the movements of the armature-levers necessary to actuate the respective repeating-keys. When the tumbler-levers are in normal position with respect to the arm 63, movement of the armature 64 toward the magnet 65 tilts the tumbler-levers about the axis of the shaft 62, so that the end of the lever 122' is 120 moved to a position slightly below the lug 125 130

- 112' and the end of the lever 122 is moved up to a position such as to substantially prevent movement of the armature-lever 3, the lug 112 engaging the end of the tumbler-lever 5 after a very slight movement of the armature-lever away from the magnet 1. Similarly, movement of the armature 64 toward the magnet 65', raises the end of the tumbler-lever 122' and lowers the end of the tumbler-lever 122, so that the end of the latter is below the lug 112 and permits free movement of the armature-lever 3, while movement of the armature-lever 3' is prevented by the tumbler-lever 122'.
 10 In addition to the main coils of the tumbler-magnets 65, 65', said magnets have auxiliary coils or windings 74, 74' which are connected with condensers 75, 75' as herein-after described, the condensers being conveniently located in the base of the repeating-instrument beneath the plate 20, as shown in Figs. 2 and 4.
 15 Referring now especially to Fig. 1, there is represented diagrammatically all of the parts of the repeating instrument immediately concerned in the operation thereof, together with certain auxiliary mechanism located at the repeating-station, and also the essential mechanism located at the terminal-stations of the east and west lines. The said mechanism located at the east and west terminal-stations comprises the relays 76, 76', the operators' keys 77, 77', generators 78, 78', and ground connections g , g' . The auxiliary mechanism located at the repeating-station comprises the operators' keys 79, 79', spring-jacks 80, 80', wedges 81, 81' for engaging said jacks, and shunt-relays R, R' which are connected with said wedges and the repeating instrument as hereinafter described. There may also be provided at the repeating-station a pair of ordinary sounders 82, 82' and local batteries B, B' for operating the same. The shunt-relays R, R' comprise electromagnets 83, 83' having pivoted armatures 84, 84' adapted to actuate keys 85, 85', the arrangement of the keys being similar to that of the repeating-keys actuated by the transmitter-magnets. Suitable springs are provided, as shown, for pulling the relay-armatures away from the magnets toward stop-screws therefor, and for pulling the keys 85, 85' toward contact-screws 86, 86'. Stop-screws are also provided for limiting movements of the keys away from the contact-screws 86, 86'. The adjoining ends of the armatures and keys are provided with contact-pins through which the keys and armatures are electrically connected with each other when the armatures are drawn toward the magnets. The armature 84' and key 85' are shown in the positions assumed when the magnet 83' is not energized, and the armature 84 and key 85 are shown in the posi-
 20 tions assumed when the magnet 83 is energized, although the illustrated connections of the latter instrument are such that the magnet thereof would not be energized. Said discrepant illustration is employed in order to show the parts of one of the shunt-relays in position opposite to those of the other.
 25 The contact-screw 86 of the shunt-relay R is electrically connected with the binding-post 23 of the repeating instrument, the armature 84 is connected with one side of the wedge 81, the other side is connected with one coil-terminal of the magnet 83, and the other coil-terminal is connected with the key 85. The shunt-relay R' is similarly connected with the wedge 81' and the binding-post 23' on the repeating instrument.
 30 When the sounders 82, 82' and local batteries B, B' are employed, the same are connected, respectively, in series between the pairs of binding-posts 25, 26 and 25', 26', as represented by dotted lines in Fig. 1. The binding-posts 25 and 26 are connected with the switch-contacts 37' and 36', the binding-posts 25' and 26' being similarly connected with the switch-contacts 37 and 36.
 35 Referring now to the line-circuit connections of the apparatus, when the triple-pole "cut-apart" switches are in the positions shown in Fig. 1 and the shunt-relay wedges 81, 81' are not inserted in the jacks 80, 80', the east line-circuit may be traced as follows: Beginning with the ground g of the east terminal-station, the line connects serially the generator 78, operator's key 77 and the relay 76 at the terminal-station; thence passes to the repeating-station and connects serially the operator's key 79, the jack 80, binding-post 22, transmitter-magnet coil 1, tumbler-magnet coil 65, switch-contact 34, switch-blade 28, contact-screw 10, repeating-key 7, switch-blade 27, switch-contact 33, and binding-post 24, thence passing to ground G. Under the conditions stated, the west line-circuit may be traced through the corresponding but opposite parts of the apparatus. In addition to the before mentioned connections, the shunt-key 56' is connected by a conductor a with one terminal of the tumbler-magnet coil 65, the contact-screw 58' is connected by a conductor b with the other terminal of the coil 65, and the terminals of the coil 65' are similarly connected with the shunt-key 56 and contact-screw 58 by conductors a' and b' . Thus, when the shunt-keys are in the closed positions thereof, the same short-circuit the respective coils 65, 65', and when said shunt-keys are in the normal or open positions thereof, shown in Fig. 2, the east and west line-circuits will pass, respectively, through the coils 65 and 65'. One terminal of the coil 74 is connected by a conductor c with the repeating-key 7, the other terminal of 130

said coil is connected by a conductor *d* with one side of the condenser 75, and the other side of the said condenser is connected with the contact-screw 10. The coil 74', condenser 75', contact-screw 10' and repeating-key 7' are similarly connected with each other by means of the conductors *c*' and *d*'.

When the shunt-relay wedges are inserted in the jacks therefor the line-circuits are

- 10 thereby looped through the shunt-relays, and alternative paths are provided for the main-line currents accordingly as the shunt-relay magnets are or are not energized sufficiently to move their armatures toward them. The path provided in one instance is indicated at the relay R, the closed line extending from one side of the wedge 81 to the coil 83, thence to key 85, thence to armature 84, and thence to the opposite side of the wedge 81. The alternative path is indicated at the relay R', the closed line in this case extending from one side of the wedge 81' to the coil 83', thence to the key 85', thence through the contact-screw 86' to the 25 binding-post 23'. The binding-posts 23, 23', are connected, respectively, by conductors *c* and *w* with the portions of the line-circuits extending between the transmitter-magnet 1 and tumbler-magnet 65, and between the 30 transmitter-magnet 1' and tumbler-magnet 65'. Thus it will be seen that, when the shunt-relays are in use and the keys thereof are in closed position, the line-circuits will not pass through the transmitter-magnets, and 35 and when the shunt-relay keys are in open position the line-circuits will pass through the transmitter-magnets. The shunt-relay magnets are preferably wound to a lower resistance than the transmitter-magnets, and 40 said relays are constructed and adjusted so as to be operable with a minimum variation of current through the coils thereof.

The operation of the mechanism as a whole may now be clearly understood. Under 45 favorable operating conditions, as where there is no excessive line-leakage, the shunt-relays need not be made use of, and the operation of the mechanism will be first described without reference to said relays, and 50 assuming that the wedges 81, 81' are both withdrawn from the respective jacks 80, 80'. In the normal condition of the apparatus, both the east and west line-circuits are closed, energy for the respective circuits being derived from the generators 78, 78' at 55 the east and west terminal-stations. In the repeating instrument the transmitter-magnets are both energized, causing the respective shunt-keys 56, 56' to be held in open 60 position, and allowing the repeating-keys 7, 7' to remain in closed position. The tumbler-magnets are both energized, and the arm 63 of the tumbler-mechanism may be in contact with either of the stop-screws 69, 69', the tumbler-magnets being so adjusted

and the tumbler-levers being so balanced that while both line-circuits are closed said arm 63 will remain indiscriminately in either position to which it may have been moved. The repeating-keys, being closed, 70 furnish connections through the coils 74, 74' between the opposite sides of the condensers 75, 75', so that normally said condensers are not charged.

Assuming that the operator's key 77' at 75 the west terminal-station be opened, as shown in Fig. 1, or that an operator at any station on the west line-circuit opens said circuit in a similar manner, the immediate effect of such opening of the circuit will 80 be a decrease in the amount of current flowing through the various instruments in said circuit; and the current will continue to decrease (with greater or less rapidity, according to the resistance, leakage, capacity, 85 inductance, and other factors controlling the flow of current) until the circuit is again closed, or until it has been open a sufficient time for all current to cease. It will be understood, of course, that, in practice, telegraphic signals are transmitted by 90 fluctuations of the current in the circuit, rather than by complete cessation and re-establishment of the flow of electrical energy therein; and that in any case the operating conditions must be such that all instruments in the circuit will be operated with sufficient rapidity for the transmission of the signals, by the fluctuations of current caused in the circuit by the opening 95 and closing thereof at the sending instrument.

Immediately, therefore, upon the opening of the operator's key 77', the energization of the transmitter-magnet 1' and tumbler-magnet 65' will begin to decrease, and two actions will result therefrom, as follows: First, the armature 64 will be actuated by the tumbler-magnet 65 (which at this moment is still fully energized by the east line-current) and the tumbler-mechanism thereby tilted to the position shown in Fig. 1, which may be designated as the "west-control" position thereof; or, if the tumbler mechanism is already in said position, it will be so retained by the then predominant attraction of the magnet 65 upon the armature 64. Second, the armature-lever 3' is released, and during its movement away from the magnet it first permits the shunt-key 56 to engage the contact-screw 58, and then actuates the repeating-key 7 to open the east line-circuit at the contact-screw 10. When the east line-circuit is thus opened, the armature-lever 3 of the magnet 1 is released, but said armature-lever is prevented by the tumbler-lever 122 from moving so as to open the west line-circuit at the repeating-key 7', and said circuit is thus kept intact through the repeating-station. 130

When the east line-circuit is opened by the repeating-key 7 the tumbler-magnet 65 becomes deenergized, of course, but the tumbler-mechanism, being then in the west-control position, remains in said position in the absence of an actuating force tending to move it. At the moment of opening the repeating-key 7, the connection between the two sides of the condenser 75 is broken, and 10 said condenser then becomes charged, since the two sides thereof are then in connection with sources of different electrical potential. The charging of the condenser 75 causes a momentary flow of current through 15 the coil 74.

When the west line-circuit is again closed at the operator's key 77', the transmitter-magnet 1' is reenergized, the armature-lever 3' is thereby returned to normal position, 20 and the apparatus is restored throughout to the normal condition thereof. The return of the apparatus to normal condition involves certain actions, however, which should be considered in detail. After the 25 closing of the west line-circuit and while the transmitter-magnet 1' is being reenergized, but before the armature-lever 3' is moved thereby, the current of the west line-circuit passes through the short-circuit or 30 shunt provided by the shunt-key 56, instead of passing through the tumbler-magnet coil 65' and thereby energizing said tumbler-magnet. The reenergization of said tumbler-magnet is thus delayed until the shunt-key 35 56 is re-opened at the completion of the return movement of the armature-lever 3', and meanwhile the east line-circuit is closed at the repeating-key 7 and a flow of current thus commenced through the coil 65.

Were it not for the action of the shunt-key, 40 the magnet 65' would begin to be reenergized prior to the magnet 65, thereby tending to move the tumbler-mechanism away from the west-control position thereof; and 45 if the tumbler-mechanism were moved with sufficient rapidity the lever 122' might be caused to strike the lug 112' and retard the return movement of the armature-lever 3'. The operation of the tumbler-mechanism 50 is also affected more or less by the condensers. As before mentioned, the opening of the repeating-key 7 results in charging of the condenser 75, and so upon the closing of said key the condenser is discharged and 55 again causes a momentary flow of current through the coil 74. The discharge of the condenser occurs at such a time that it may assist the east line-current in reenergizing the tumbler-magnet 65, and thus tend to 60 prevent movement of the tumbler-mechanism away from the west-control position thereof.

The apparatus is operative without the use of the condensers 75, 75', but it has been 65 found that the action of the condensers sup-

presses certain unnecessary and undesirable movements of the tumbler-mechanism during the transmission of signals by the repeater, and causes the tumbler-mechanism to remain inert after its initial movement to 70 the west-control or east-control position, accordingly as the west line-circuit or the east line-circuit is opened at a time when the other is closed.

It will be obvious that the opening of the 75 east line-circuit at any point other than the repeating-key 7, will interrupt the sending of signals from the west-line-circuit through the repeating-station, because after such opening of the east line the next closure of 80 the west line-circuit will result in reversing the position of the tumbler-mechanism, which will give the control of the apparatus to the eastern operator by permitting opening of the west line-circuit at the repeating- 85 station. It will also be apparent that the action of the repeating mechanism is fully reversible, or that an operator at any station on the east line-circuit can cause signals to be transmitted through the repeating-station 90 to the west line-circuit, the various operations of the repeating instrument being the same as hereinbefore described but being made by the opposite parts thereof.

When desired, or when necessitated by adverse operating conditions, the shunt-relays R, R' may be made use of to increase the sensitiveness, as a whole, of the mechanism at the repeating-station. Said shunt-relays are placed in operation by inserting the 100 wedges 81, 81' in the spring-jacks 80, 80', and as the circuit-connections thereby established have been hereinbefore described, it will be sufficient to point out here the actions resulting from the introduction of said instruments. Assuming, as before, that an operator on the west line-circuit opens said circuit, the magnets 83' of the shunt-relay R' will quickly respond to the reduction of current in said circuit, and the armature 84' 105 will be released. The first slight movement of the armature 84' will permit the key 85' to engage the contact-screw 86', thus shunting the line-circuit through the conductor w, and immediately thereafter the continued 110 movement of the armature will disengage the same from the key, so that the alternative connection through the transmitter-magnet 1' is broken, and said transmitter-magnet is 115 thus instantly removed from the circuit. By 120 such complete cutting-out of the transmitter-magnet from the circuit, the deenergization thereof occurs with great rapidity, and much greater fluctuations of its magnetization are made available for use in actuating its armature-lever and the repeating-key and shunt-key which it controls. Moreover, the reduced resistance in the line-circuit, due to the removal of the transmitter-magnet therefrom, enables the current in said circuit to 125 130

build up more rapidly when the circuit is again closed by the sending operator. The increased current is then suddenly diverted to again pass through the transmitter-magnet, as the shunt-relay resumes its normal position and opens the key 85', after first restoring the connection between said key and the armature 84'.

The fluctuations of current in the east line-circuit will cause similar operations of the shunt-relay R, which will thus alternately remove from and introduce into said circuit the resistance of the transmitter-magnet 1, so that the pulsations of current in the east or receiving-circuit will be greater than if caused only by the opening and closing of said circuit by the repeating-key 7.

From the foregoing it will be seen that my invention provides a repeating mechanism of relatively simple construction, employing direct-repeating transmitters which are actuated solely by energy derived from the connected main-line circuits; and that it is not essential to the operation of the repeating mechanism to have either local or main-line batteries or generators located at the repeating-station. Thus my repeater can be installed at any station, without regard to the provision at such station of batteries or generators, it being merely necessary that the connected line-circuits have suitable generators at the terminal-stations thereof.

The local batteries B, B', hereinbefore mentioned, are not involved in the operation of the repeating mechanism, as such, but are used only when the two line-circuits are not operatively connected by the repeating instrument. "Cutting apart" of the line-circuits is affected by turning the cams 72, 72' so as to press the tumbler-levers down to positions at which they will not interfere with the movements of the armature-levers 3, 3'; and reversing the positions of the triple-pole switches, so that the blades of said switches engage the contact-posts 36, 37, 38, 36', 37' and 38', as represented by dotted lines in Fig. 1. By movement of the switches to said positions, the repeating-key 7 and contact-screw 10 are removed from the east line circuit, and are connected in a local sounder-circuit through the battery B', sounder 82', binding-post 26', switch-contact 36, switch-blade 27, key 7, contact-screw 10, switch-blade 28, switch-contact 37, and binding-post 25'; while the line-circuit, instead of passing to the repeating-key through the switch-contact 34 and switch-blade 28, passes through the switch-blade 29 and switch-contact 38 directly to ground. The other switch causes like connections to be formed between the repeating-key 7' and sounder 82, removing said repeating-key from the west line-circuit and connecting said circuit through the switch-contact 38' to ground. When the described connections are

established, the repeating-keys operate as relay-contact for controlling the local sounder-circuits, and an operator at the repeating-station may use the key 79 to communicate with stations on the east line-circuit, or use the key 79' to communicate with stations on the west line-circuit. The repeating-station operator may thus test the operation of each line-circuit independently of the other, and adjust each of the repeating-transmitters for proper operation on the line-circuit with which it is connected. The repeating-station operator, having both sides of the repeating instrument in proper adjustment, may then reverse the positions of the triple-pole switches, turn the cams 72, 72' so as to release the tumbler-mechanism, and then test the operation of the repeating mechanism as a whole, using either of the keys 79, 79', and making any final adjustment that may be necessary.

Now, having described my invention, what I claim and desire to secure by Letters Patent is:

1. The combination with two line-circuits, of transmitters connected one in each circuit and each adapted to open and close the other circuit, members movable to positions at which they will prevent movement of the respective transmitters to circuit-opening position, and means actuated directly by energy from the line-circuits for actuating said members.

2. The combination with two normally-closed main line-circuits, of transmitters connected one in each of said circuits and each adapted to open and close the other circuit, and means actuated directly by energy from said line-circuits for preventing movement of each of the transmitters to circuit-opening position when the other transmitter is in circuit-opening position.

3. The combination with two main telegraphing circuits, of transmitters connected one in each of said circuits, each transmitter controlling contacts for opening and closing the other circuit, and means in connection with and actuated by energy from each circuit to prevent movement of the transmitter in said circuit to circuit-opening position when the other circuit is open.

4. In a telegraphic repeating mechanism, the combination with two line-circuits, of transmitters connected one in each line-circuit, each transmitter being actuated by energy from its respective line-circuit and being adapted to open and close the other line-circuit, and means actuated directly by energy from the respective line-circuits for selectively preventing movements of the transmitters in accordance with the origin of current variations in the line-circuits.

5. In a telegraphic repeater, paired sets of apparatus, each set including a transmitter-magnet, an armature-lever actuated

5 by said magnet, a repeating-key and a shunt-key actuated by movements of said armature-lever, and a tumbler-magnet connected electrically with the transmitter-magnet, circuits connecting each repeating-key with the transmitter-magnet of the other set of apparatus, electrical connecting means between each shunt-key and the tumbler-magnet of the other set of apparatus, and tumbler-10 mechanism controlled by the tumbler-magnets and adapted to limit selectively the movements of the armature-levers.

6. In a telegraphic repeating apparatus, the combination with two line-circuits, of 15 transmitters connected one in each line-circuit and each adapted to open and close the other line-circuit, tumbler-magnets connected one in each line-circuit, tumbler-levers actuated by the tumbler-magnets and 20 each adapted to limit movement of one of the transmitters, and a key actuated by each transmitter and controlling a shunt for the tumbler-magnet of the circuit through the respective transmitter.

25 7. In a telegraphic repeater, a line-circuit, a transmitter having an electromagnet connected in said circuit, and a relay in said circuit adapted to remove the transmitter-magnet from the circuit upon a decrease of 30 current therein, and restore the transmitter-magnet to the circuit upon an increase of current therein.

8. In a telegraphic repeating apparatus, two line-circuits, a transmitter controlled 35 by one line-circuit and adapted to open and close the second line-circuit, stopping means for preventing movement of the transmitter to circuit-opening position, and means actuated by energy from the second line-circuit for moving the stopping means to release the transmitter when the circuit controlling said transmitter is opened prior to opening of the second line-circuit.

9. In a telegraphic repeating apparatus, 45 the combination with two line-circuits, of transmitters in each line-circuit, each adapted to open and close the other line-circuit, tumbler-magnets in each line-circuit, tumbler-levers actuated by the tumbler-magnets and each adapted to limit movement of one of the transmitters, an auxiliary winding for each tumbler-magnet, and condensers connected so as to be discharged through said auxiliary windings upon movement of 50 the respective transmitters to circuit-closing position.

10. In a telegraphic apparatus, an electromagnet, an armature adapted to be actuated by said electromagnet, a key arranged to be 60 engaged and actuated by said armature, a contact normally engaged by said key, the key being disengageable from said contact by continued movement of the armature after the same engages the key, a line-circuit connected through said electromagnet to the 65

key, and separate connections from the armature and from the key-contact for completing said line-circuit, whereby movements of the armature will establish the line-circuit alternately through said connections 70 without opening the circuit.

11. In a telegraphic repeating instrument, the combination with two line-circuits, of a transmitter for each circuit, each transmitter having contacts forming part of the other 75 circuit whereby the circuits are reciprocally openable, a stop device having a gravitational bias to positions at which it will prevent movement of one or the other transmitter to circuit-opening position, and means 80 actuated directly by energy from said line-circuits to selectively control said stop device.

12. In a telegraphic repeating instrument, two line-circuits, transmitters connected one 85 in each line-circuit, each transmitter having and actuating a single movable contact connected in and adapted to make and break the line-circuit through the other transmitter, a stop movable to positions for preventing 90 either transmitter from actuating its contact to open the line-circuit through the other, and means actuatable directly by energy from each line-circuit to move the stop.

13. In a telegraphic repeating apparatus, 95 the combination with two line-circuits, of two transmitters connected in said circuits and each actuatable by energy from its respective circuit to open and close the other circuit, said transmitters being normally in 100 circuit-closing position, a stop device movable to and normally positioned at one of two blocking positions at which it will retain the respective transmitters at normal position, and means actuatable by energy from 105 the respective line-circuits each to actuate the stop device to or retain the same at its blocking position with respect to the transmitter actuated from the same circuit.

14. In a telegraphic repeating apparatus, 110 line-circuits, a transmitter for each circuit connected therein and actuated by energy therefrom and controlling contacts connected in the other circuit whereby the latter may be opened and closed, each circuit constituting a sending-circuit with respect to the other as a receiving-circuit, a mechanical stop device movable to blocking positions such as to prevent movement of the respective transmitters to circuit-opening position, 115 and electrical actuating means for the stop device connected with the circuits so that energy from the receiving-circuit will move the stop to the blocking position for the transmitter in the receiving-circuit upon 120 opening of the sending-circuit.

15. In a telegraphic repeating apparatus, line-circuits, a transmitter for each circuit connected therein and actuated by energy therefrom and controlling contacts con- 130

nected in the other circuit whereby the latter may be opened and closed, each circuit constituting a sending-circuit with respect to the other as a receiving-circuit, a stop device 5 movable to blocking positions such as to mechanically prevent movement of the respective transmitters to circuit-opening position, electrical actuating means for the stop device connected with the circuits so that energy from the receiving-circuit will move 10 the stop to the blocking position for the transmitter in the receiving-circuit upon

opening of the sending-circuit, and means for applying energy from the sending-circuit to retain the stop in blocking position 15 with respect to the receiving-circuit transmitter.

In testimony whereof I have hereunto subscribed my name in the presence of two witnesses.
